UNITED STATES PATENT OFFICE.

HOWARD M. DU BOIS, OF DETROIT, MICHIGAN

PROCESS OF ELECTROLYSIS.

1,075,026.

Specification of Letters Patent.

Patented Oct. 7, 1913.

Application filed April 11, 1910. Serial No. 554,605.

To all whom it may concern:

Be it known that I, HOWARD M. DU BOIS, a citizen of the United States of America, residing at Detroit, in the county of Wayne and State of Michigan, have invented certain new and useful Improvements in Processes of Electrolysis, of which the following is a specification, reference being had therein to the accompanying drawings.

10 The invention relates to the manufacture of various products by the electrolysis of salts, being more particularly designed for use in the electrolysis of chlorid sodium and the formation of caustic soda.

15 It is the object of the invention to obtain an increased efficiency or output of the product in relation to the energy consumed, and, further, to obtain a higher concentration of the cathode liquor.

20 Still another object of the invention is to prevent the formation of hypochlorites, which have a destructive action upon the apparatus.

25 With these objects in view, the invention consists in the process as hereinafter set forth.

30 In the drawings—Figure 1 is a vertical central section through an electrolytic cell, which may be employed for carrying out my improved process; Fig. 2 is a horizontal section thereof.

35 In the electrolysis of solutions where porous diaphragms are employed, great difficulty is experienced in maintaining the porosity of the diaphragm. Consequently, the cells decrease in efficiency as the pores become clogged with impurities in the solution, the electrical resistance being increased and requiring a higher voltage and greater 40 expenditure of energy in the production of the product. My improved process is designed to a large measure overcome this difficulty without destroying the effectiveness of the diaphragm or incurring any danger of 45 commingling of the gaseous products of the electrolysis.

50 Broadly considered, the process consists in the flowing of the electrolyte over the upper end of a vertically-arranged diaphragm, and thence downward between the diaphragm and the exposed cathode surface, whereby the flowing of the cathode liquor is not dependent solely upon the porosity of the diaphragm, while the electrolytic action is un- 55 impaired.

With the apparatus as shown, A is the

cathode which forms also the outer container for the liquid in the cell. This cathode is preferably formed with vertically-extending channels B in its inner face, 60 while a porous diaphragm C is arranged adjacent to and supported by the cathode.

D is an anode formed preferably of a series of vertically-arranged bars of carbon extending around the cell adjacent to the 65 inner face of the diaphragm. These bars are secured at their upper ends to a supporting cap E which is provided with a depending annular flange F.

G is a parallel annular flange surrounding 70 the flange F but spaced therefrom and supported upon the cathode. H is another annular flange surrounding and spaced from the flange G and depending from the cap E and seated on the upper end of the cathode. 75 The construction of the annular flanges F, G and H is such that they form a seal preventing the passage of gas from one compartment to the other, but permitting the flow of liquid therebetween.

80 At the lower end of the cell is an annular channel I communicating with all of the vertically-extending grooves or passages B and having a discharge conduit J connected thereto.

85 K is an inlet for the electrolyte preferably extending through the bottom of the cell and connected with suitable means for maintaining a constant flow of the liquid therethrough.

L is a gas outlet connecting with the upper end of the anode compartment, and M is a gas outlet connected with the cathode compartment.

90 In operation, the salt solution, or other liquid to be electrolyzed, is fed into the anode compartment through the conduit K and by reason of the porosity of the diaphragm C this liquid is also brought into contact with the face of the cathode. Electrolysis will thus take place, the caustic and hydrogen gas collecting at the cathode and the chlorid gas collecting at the anode. The constant inflow of the electrolyte will not only compensate for that which passes 105 through the pores of the diaphragm, but the surplus will be forced upward through the space between the flanges F and G and into the cathode compartment, where it will descend through the channels B in the cathode. This will displace the cathode layer formed by the electrolysis and cause a con-

stant outflow of said liquor through the discharge pipe J.

- It will be noted that the electrolyte on both sides of the diaphragm is arranged in 5 to terminate the anode and the cathode, and, therefore, is maintained in the field of the electrolysis. The gases liberated at the anode and cathode will ascend through the solution, and will be collected in their respective compartments, and any commingling of these gases is prevented by the liquid seal maintained between the flanges F, G and H. There will, however, be a certain amount of the hypochlorite formed 10 during the electrolysis, since dissolved chlorine gas may pass with the electrolyte through the liquid seal and into contact with the cathode liquor. Here the hypochlorite formed will be directed in the path of the 15 liberated hydrogen which, reacting thereon, will reduce the hypochlorite to a chlorid. Here it will be directed in the path of the liberated hydrogen, which, reacting thereon, will reduce the hypochlorite to a chlorid. 20 Thus before the solution comes into contact with the metallic surface of the cathode practically all of the hypochlorite is eliminated and this prevents the corrosion and destruction of the cell.
- 25 What I claim as my invention is:
1. The process of electrolysis, which comprises flowing the electrolyte from the anode compartment through a gas-proof seal into the cathode compartment, and thence across 30 the electrolytic field within a space between the diaphragm and the cathode.
  - 35 2. The process of electrolysis, which comprises maintaining constant freedom of com-

minication between the anode and cathode compartments, and a constant flow of liquid 40 across the electrolytic field within a space between the cathode and the porous diaphragm.

3. The process of electrolysis, which comprises maintaining a constant pressure on 45 the electrolyte in the anode compartment, and a flow of liquid across the electrolytic field within a space between the porous diaphragm and the cathode, with a constant discharge of the cathode liquor.

4. The process of electrolysis, which comprises constantly feeding in electrolyte into 50 the anode compartment, in by-passing a portion of the electrolyte around the porous diaphragm, and in maintaining a flow of the liquid across the electrolytic field from the point of said bypass with a constant discharge of the cathode liquor.

5. The process of electrolysis, which comprises flowing the liquid across the electrolytic field within a space between the 55 diaphragm and the cathode.

6. The process of electrolysis, which comprises flowing the liquid across the electrolytic field in thin sheets within a space 60 between the diaphragm and the cathode.

7. The process of electrolysis, which comprises flowing the liquid across the electrolytic field downward within a space between the diaphragm and the cathode. 70

In testimony whereof I affix my signature in presence of two witnesses.

HOWARD M. DU BOIS.
